UNITED STATES PATENT OFFICE.

JOSEPH F. SCHIMEK, OF WORCESTER, MASSACHUSETTS, ASSIGNOR TO WHITIN MACHINE WORKS, OF WHITINSVILLE, MASSACHUSETTS, A CORPORATION OF MASSACHUSETTS.

TAPE CONDENSER.

Application filed January 14, 1928. Serial No. 246,765.

My invention relates to textile machines of the type known as condensers, which first separate a web of carded material into individual masses of loosely clinging fibers and subsequently, by a rubbing action, compress and cause these fibers to adhere tenaciously enough so that the individual masses, then termed roving, can be spun into yarn. In its usual form such a machine comprises a great number of endless belts, or tapes, passing over and between a pair of dividing rollers, by means of which the web is divided up into separate masses, and a plurality of sets of rubbing aprons which receive the aforesaid masses of roving from the tapes and, by a combined reciprocating motion and continuous conveying motion, rub these masses together and convey them to rolls or drums upon which they are wound preparatory to a further operation, such as spinning.

The present invention relates particularly to the rubbing or condensing mechanism and briefly stated comprises a novel arrangement of aprons by means of which a more complete rubbing of the stranded masses is possible than in any similar machine hitherto constructed. This result is achieved by causing the stranded masses to travel a greater linear distance through and between the rubbing aprons than has before been possible; this being accomplished in the machine of the present invention without increasing the overall measurement of the machine, from front to back, and with only a slight increase in the height thereof and, what is equally important, without decreasing the effectiveness of the rubbing which occurs when the moving portion of the apron is caused to bridge an excessive gap between the rollers.

In contradistinction to all prior machines, the apron mechanism of the present invention is so arranged and designed that each one of the stranded masses separated by the tapes pass between a pair of rubbing aprons, then immediately pass between a pair of aprons again, and preferably pass a third time between a pair of aprons. This is done by arranging a plurality of aprons (a greater number than two) in contiguous arrangement; and causing the material to pass between one end apron and the next adjacent apron, then back between the latter apron and a third adjacent apron, then in the original

direction between said third adjacent apron and the other end apron, which is the fourth adjacent apron.

Another object of the invention is to draw the roving more than has been hitherto possible. In prior art machines there is a draught on the carded material as it enters the dividing rollers; there is a draught on the individual strands as they pass from the tapes to the aprons, and there is a further draught on the strands as they leave the aprons on their way to the take up beams. In the machine of the present invention there exists all of the above draughts, and in addition there is a draught as the roving goes from the space between the first and the second apron, and enters the space between the second and third apron; and there is another draught as the roving goes from the second and third aprons to the space between the third and fourth aprons. This result is accomplished by causing the first and second aprons to travel at one speed, and the third and fourth aprons to travel at a greater speed, and it results in roving that is more attenuated, and better prepared for the spinning operation.

In the machine disclosed in the accompanying drawings, there are four aprons to each set and there are four sets of aprons, the latter being the usual arrangement in tape condensers. In the machine illustrated in the accompanying drawings, aprons are mounted one over the other, and in the best embodiment of the invention known to me, alternate aprons are reciprocated in opposite directions, as will hereinafter more fully appear.

The above and further objects and advantageous features of the invention will more fully appear from the following detailed description, taken in connection with the accompanying drawings, in which:—

Fig. 1 is an elevation of the right hand side of a condenser constructed in accordance with the invention, the gearing that drives the aprons being omitted.

Fig. 2 is an elevation similar to Fig. 1, but showing the apron driving gearing.

Fig. 3 is a sectional view taken on the line 3, 3 of Fig. 2, the aprons and gearing on the apron shafts being shown in elevation.

Fig. 4 is a fragmentary sectional view taken through the right hand frame member showing certain of the gearing for driv-

ing the apron shafts, this section being taken on the line 4, 4 of Fig. 2.

Fig. 5 is a fragmentary plan view of the driving mechanisms for the aprons, this view being also taken on the right hand side of the machine.

Fig. 6 is a fragmentary elevation taken on the left hand side of the machine, showing the actuating mechanisms which give 10 the aprons their reciprocatory motion.

Like reference characters refer to like parts throughout the drawings.

Referring first to Figs. 1 and 3, the machine generally comprises pair of side frames 15 1, 1 suitably attached together and between which the condensing mechanism is mounted. A pair of dividing rolls 2, 2, are mounted at the front of the machine in suitable bearings which are supported in notches 3, 3 20 provided in the frame members 1. A plurality of endless tapes 4 pass partly around and between the dividing rolls 2, 2 and travel therefrom in four separate paths, around guiding rolls 5, 5, one of which 25 carries all the tapes from the lower dividing roll 2; the other carrying all the tapes from the upper dividing roll 2; both sets of tapes dividing into two lots after passing over the rolls 5, 5 ultimately passing 30 to rolls 6 and 7 in the upper half of the machine and 8 and 9 in the lower half. From the rolls 6, 7, 8 and 9 the endless tapes 4 are carried back to the dividing rolls 2, 2 by means of guiding rolls 10, 10 35 and 11, 11.

The foregoing will serve as a sufficient description of the dividing mechanism of the machine, since dividing mechanisms for condensing machines are well known, and 40 it will be readily understood that any desired arrangement of the tapes and rollers may be employed, since the present invention relates to the rubbing or condensing mechanisms. The latter are located in two upper 45 openings 12 and 13 and two lower openings 14 and 15 provided by each frame member 1, and as the separate rubbing apron units mounted in said four openings are identical only one need be described in detail. Each unit comprises four superimposed aprons 16, 17, 18 and 19. The apron 16 passes around and is supported by rollers 20, 20; the apron 17 passes around and is supported by rollers 21, 21; the apron 18 50 similarly passes around and is supported by rollers 22, 22; while the apron 19 passes around and is supported by rollers 23, 23.

Referring now to Figs. 1, 3 and 6, rolls 60 20, 20 of each upper apron 16 are rotatably supported in end brackets 24, 24. These end brackets 24, 24 in the case of the aprons located in the openings 12 and 14, are secured to the frame members 1, 1 by any suitable fastening means such as bolts 12^a and 14^a. 65 The end brackets 24, 24 that are located in

the openings 13 and 15 provide upwardly projecting bosses 24^a, 24^a which are secured to the frame members 1, 1 by bolts 24^b and slots 24^c, by reason of which their position is adjustable in a vertical direction. 70 The rolls 21, 21 of the aprons 17 are rotatably supported in end brackets 25, 25 which are secured to end brackets 24 by means of bolts 25^b passing through projecting portions 25^a of the brackets 25 and through the 75 brackets 24.

The rollers 22, 22 are rotatably supported in end brackets 26, 26 and the rollers 23, 23 are supported in end brackets 27, 27; each of the brackets 26 providing a depending projecting portion 26^a, by means of which it is fastened to a bracket 27. The brackets 27, in the case of the apron mechanisms located in the openings 13 and 15, are attached to the frame members 1, 1 by bolts 13^b and 15^b in precisely the same manner that the brackets 24 are attached to the said frame members in the case of the mechanisms located in the openings 12 and 14 as already described. The brackets 27 80 located in the openings 12 and 14 are adjustably attached to the frame members 1, 1 by means of depending bosses 27^a, 27^a similar to the bosses 24^a, which are however, in staggered relation to the latter to conserve space, as shown in Fig. 1. The foregoing mounting for the aprons is in many respects similar to that shown in Reissue Patent No. 15,778 except for changes made necessary by the fact that, in case of the 85 present invention, double the number of aprons are provided in each frame opening of the machine, and the provision of the staggered bosses 24^a and 27^a; for the details of the method of adjusting and support of the several sets of rollers 20 to 23 inclusive, reference should be to the aforesaid patent.

The machine of the present invention, in common with prior condensing machines, provides mechanism for driving the several 110 sets of aprons 16, 17, 18 and 19, such driving means being positive in its nature, that is to say, each apron is driven independently and not dependent upon the frictional drive from any other apron. This mechanism is 115 best illustrated in Figs. 2, 3 and 4. My machine further provides mechanism for reciprocating the several sets of aprons, this being illustrated in Figs. 3 and 6.

Having reference first to the driving mechanism, the number of aprons being double that provided in prior machines of this character, I have found that sprocket and chain driving means can be employed to great advantage, as this eliminates many gears which would otherwise be necessary. Referring now to Fig. 2, a large pulley 28 is provided on one side of the machine, this pulley being fastened to a shaft 29 which also carries a spur gear 30. The pulley 28, 120 125 130

which is driven from any outside source of power, is broken away in Fig. 2 to better show the other elements of the driving mechanism. The gear 30 meshes with and 5 drives a gear 31 on a shaft 32 which carries a smaller spur gear 33, said gear 31 being also broken away as in the case of the pulley 28. The gear 33 meshes with the lower of a pair of similar intermeshing 10 gears 34, 34 which are carried by the roll shafts that support the dividing rolls 2, 2. In this manner said rolls 2, 2 are actuated to drive the tapes 4 and a pair of spur gears 35, 35 mounted on studs 36, 36 in mesh 15 with the gears 34, 34 are also driven thereby. Desirably formed integral with the gears 35, 35, as shown in Fig. 5 are sprocket gears 37, 37 which are thus positively rotated by the train of gearing described. Around the 20 sprockets 37, 37 pass sprocket chains 38 and 39 in the case of the upper and lower sprockets 37 respectively, and these chains 38, 39 actuate the apron driving mechanism.

The several sets of rolls 20, 21, 22 and 23 25 are driven through gears 40 fastened to the shafts of the rollers 20 and gears 43 fastened to the shafts of the rollers 23. These spur gears 40 and 43, four of each of which are provided as shown in Fig. 3, are wide gears 30 because of the reciprocating motion imparted to all of the apron rollers 20 to 23 inclusive which will be hereinafter described. The gears 40 mesh with gears 41 fastened to the shafts of rollers 21, and the gears 43 mesh 35 with gears 42 fastened to the shafts of the rollers 22. The gears 40 are located close to the frame members 1, although, of course, they move slightly relative thereto while the gears 43 are spaced a considerable distance 40 from the frame members 1, 1 even when they are closest thereto. The gears 40 are driven by the several gears 44, 45, 46 and 47 which, as best shown in Fig. 4, are located in the same vertical plane, and are rotatably 45 mounted on studs 44^a, 45^a, 46^a and 47^a fastened to the frame 1; the position of these gears 44, 45, 46 and 47 in elevation being clearly shown in Fig. 2. Each of the aforesaid four gears has integrally attached 50 thereto sprocket wheels 48, 49, 50 and 51 respectively, around which pass the chain 38 in the case of the wheels 48 and 49, and the chain 39 in the case of the wheels 50 and 51.

The wide gears 43 are driven by spur 55 gears 52, 56, 54 and 55 which are located in the same vertical plane and are mounted on studs 52^a, 56^a, 54^a and 55^a attached to the frame 1. The gears 52, 54 and 55 have sprocket wheels 57, 59 and 60 integrally attached thereto, the sprocket chain 38 passing over the wheel 57 and the sprocket chain 39 driving the last two wheels 59 and 60. The gear 56 is driven indirectly by means of a spur gear 53 mounted on a stud 53^a to which 60 is integrally attached a sprocket wheel 58

around which the chain 38 also passes, the reason for this indirect drive being that otherwise the gear 43 in the frame opening 13 would be driven in the wrong direction.

The course of the chains 38 and 39 will 70 now be pointed out. It is necessary to pass these chains around the several sprocket wheels in such a manner that a sufficient contact and pressure of the chain against each sprocket wheel will be had so that there will 75 be no danger of the chain jumping off, and at the same time the direction of travel must be so arranged that the aprons which are finally driven will be moved in the right direction. As the function of the aprons is 80 to take the separated carded material from the tapes 4, 4 adjacent the rollers 6, 7, 8 and 9, respectively and to condense the several strips of material into roving, the travel of the aprons must be in the direction of the 85 small arrows shown in Fig. 2. The sprocket chain 38 consequently moves upwardly after leaving the driving sprocket 37 partially around an idler roll 61 to the sprocket wheel 48, this being therefore the slack side of the 90 chain. After leaving the sprocket wheel 48 on the side facing towards the rear of the machine, the chain 38 passes over the sprocket 57 at the front thereof, then down around the sprocket 49 at the rear thereof, 95 around the same side of the sprocket 58 and back around the driving sprocket 37. The interposition of the intermediate spur gear 56 is made necessary by the fact that the chain 38 can not pass over the front of the 100 sprocket 58, as to do so would not give it enough contact therewith.

The chain 39 moves in the direction of the arrow shown in Fig. 2, the slack downwardly moving side thereof being supported, as in 105 the case of the chain 31 by an idler roll 62. Thence the said chain passes around the sprocket wheel 60 leaving said wheel on the rear side thereof, then upwardly around the sprocket 51 on the front side thereof, then 110 around the back side of the sprocket 59 and the front of the sprocket 50. At this point it is necessary to introduce an additional sprocket in order that contact may be maintained between the chain 39 and the sprocket 115 50 and to this end a sprocket 63 is provided, located just above the sprocket 50 on a stud 63^a (see Fig. 4) there being a spur gear 64 fastened to the sprocket 63 to drive the take-up mechanism of the machine, with which 120 the present invention has nothing to do.

The mechanism for imparting a reciprocatory movement to the aprons is best shown in Figs. 3 and 6, and comprises a vertical shaft 65 mounted in bearings 66, 67 and 68 spaced from the left hand side of the machine by means of brackets 69, 70 and 71. This shaft has a pulley 72 fastened to it at its lower end, thus to rotate said shaft by means of a belt drive, not shown. Spaced 130

along said shaft 65, opposite the openings 12, 13, 14, and 15 respectively, are eccentrics 73 which are surrounded by yokes 74 so that rotation of the shaft 65 causes oscillation of 5 the yokes 74.

The yokes 74 provide tongue portions 75 that are pivotally connected by means of pins 76 to a plurality of connectors 77 and 78, each of which provides a forked portion 10 79 for the reception of the tongue portions 75. Each connector 77 is of the shape shown in Figs. 3 and 6, and the top leg 77^a thereof is fastened to a bar 80 that controls the longitudinal position of the shafts 20, there being 15 four of such bars, one for each pair of shafts. The lower portion of each connector 77 is forked, and the bottom legs 77^b thereof are fastened to a bar 82 that similarly controls a pair of shafts 22, there being likewise four 20 of such bars 82. Each connector 78 is symmetrical and its top leg 78^a is fastened to a bar 81 controlling shafts 21, while its bottom leg 78^b is fastened to a bar 83 controlling shafts 23.

25 The shafts 20 to 23 inclusive extend beyond the end brackets 24 to 27 inclusive and are rotatably held by the bars 80 to 83 inclusive by means of nuts 84 and washers 84^a coacting with threaded end portions of 30 the several sets of shafts. One end of each bar 80 to 83 inclusive is provided with a slot 85 (see Fig. 6) in substantial alignment with slots 86 provided in the brackets 24 to 27 inclusive, the latter being more fully described in the aforesaid reissue patent, so that relative lateral movement of the parts is thus permitted. As will be observed from Fig. 3, the top one of each pair of eccentrics 73 occupies the same angular position, 35 while the bottom eccentric 73 of each pair is spaced angularly one hundred and eighty degrees from the top one. The result is that when the yokes 74 that are pivotally secured to the conductors 77 are farthest to the right 40 (Fig. 3) the yokes secured to the connectors 78 are farthest to the left. The connectors 77 and 78, therefore, are either moving in opposite directions or they are at extreme opposite positions, and as the connector 77 controls the top and the third aprons 16 and 18 in each frame opening, and the connector 78 controls the second and the bottom aprons 17 and 19, it follows that the aprons, 45 wherever they come in contact, are moving in opposite directions (laterally) except at the moments of reversal.

The connectors 77 and 78 are fastened to the several bars 80 to 83 inclusive, by means of bolts 87 and nuts 88 which can be seen 50 in Fig. 6. It will be obvious that the relative position of the connectors 77 and 78 can be reversed, and in fact any arrangement utilized that permits the bars 80 and 82 to be reciprocated in unison, while the bars 81

and 83 are moved in unison, but in the opposite direction. 65

The machine operates, as do similar prior art machines, in connection with a carding machine, the product of which is a web of fibers that have been carded and caused to lie generally in one direction. Such web is led to the dividing rolls 2, 2 by means of an apron, not shown, or any other suitable conveying means. Immediately upon its entrance between the dividing rolls 2, 2, the web is split into a multitude of longitudinal strips, one-half of which thereupon travel around the back side of the upper roll 2 and the front side of the upper guiding roll 5, and the other half of which travels downwardly in similar fashion around the lower rolls 2 and 5. Leaving the rolls 5, 5 in two divisions, the web is further divided, one-quarter of the tapes carrying it directly to the roll 6, another quarter carrying it to the rolls 7, a third quarter to the roll 8 and the remaining quarter to the roll 9. Between the rolls 5, 5 and the rolls 6, 7, 8 and 9, the tapes undergo a twist as illustrated at *x*, *x*, Fig. 1, and the longitudinal filaments of 80 carded material are on the outside of the tapes as they pass around the several rolls 6, 7, 8 and 9.

The foregoing is merely descriptive of one form of tape dividing mechanism and in this embodiment the tapes going around the roll 6 pass upwardly toward the roll 10, and in so doing pass tangentially to the apron 16 which removes the separate strands of carded material from said tapes and conveys 90 them rearwardly of the machine between the aprons 16 and 17. In similar fashion, the tapes that pass around the roll 7 pass upwardly tangent to the apron 16 in the opening 13 and the stranded material therefrom moves rearwardly between the second pair of aprons 16 and 17. Also, the tapes moving downwardly around the roller 8 pass tangent to the apron 17 in the opening 14 and those tapes passing around the roller 9 contact with the apron 17 in the opening 15, and thus that portion of the stranded material going to the lower half of the machine is conveyed rearwardly in two parts between the pairs of aprons 16 and 17 in the 110 spaces 14 and 15 respectively. 115

At this point there is a draft on the material from the fact that the aprons 16 and 17 are travelling at a slightly greater speed than the tapes 4, this being the usual arrangement in condensers. The material is now rubbed and condensed by the reciprocal action of the several pairs of aprons 16 and 17 from which it passes rearwardly down around the rear roll 21 in each case and then between the pairs of aprons 17 and 18. The gearing on the side of the machine illustrated in Figs. 2, 3 and 4 is so arranged 120 125

that the wide gears 43 are driven at a slightly greater speed than the wide gears 40. Inasmuch as the gears 40 mesh with and drive the gears 41, while the gears 43 mesh with 5 and drive the gears 42, it follows that the aprons 16 and 17 will travel at one rate of speed, while the aprons 18 and 19 will travel at a different and slightly higher rate of speed, the gears 40, 41, 42 and 43 being all 10 of the same diameter and number of teeth. The stranded material, therefore, in passing between the aprons 17 and 18 after leaving the aprons 16 and 17 is still more attenuated and drawn out since apron 18 is going at a 15 greater speed than apron 17. It has been found in practice that it is immaterial that the apron 17 is moving at a different and lower rate of speed from the apron 18, since the difference is slight and the material tends 20 to travel at a speed which is the mean of the velocity of these two aprons 17 and 18 and any differential in the movement tends to condense the material much as the lateral reciprocatory motion does.

25 The material next travels forward as indicated by the arrow in Fig. 2 and then moves downwardly around the front roller 22 and in between the aprons 18 and 19. There is a further draft at this point, since both of 30 the aprons 18 and 19 are travelling at a higher rate of speed than the mean velocity of the material between aprons 17 and 18. The material now moves rearwardly and is further rubbed and condensed by the relative reciprocatory motion of the aprons 18 and 19, and finally passes out of the aprons 35 altogether, between a set of comb dividers 89, and ultimately to take-up rolls 90 upon which they are wound by the action of the 40 cylindrical take-up drums 91 in the usual manner. There is, of course, a draft on the roving between the drums 91 and the last set of aprons 18 and 19, as is common in such machines.

45 It should be observed that, owing to the alternate reciprocation of the rollers 16 and 18 in one direction and the rollers 17 and 19 in the other direction, the material is subjected to a rubbing action no matter 50 which particular set of aprons it happens to be located between. Thus in my improved condenser the material is subject to the rubbing action through a far greater distance than has been possible with any prior machines, and yet the machine of the present 55 invention is of the same dimensions from front to rear as the prior machines and is only slightly higher. Also, according to my invention two additional drafts on the material 60 are now provided for, the machine of the present invention contemplating five separate drafts, first as the web of carded material enters it, the second, as it leaves the tapes going to the apron, two drafts in the

apron mechanism itself, and a final draft as 65 it is wound upon the take-up rolls.

It may be desirable, to save the operator the trouble of causing the separate ends of stranded material to thread themselves properly between the several sets of aprons, to 70 provide guiding rollers 92 projecting forwardly of the aprons 18 to guide the stranded material downwardly. It will be noted that the aprons 18 are offset with respect to all the other aprons; this is to prevent 75 the stranded material from being picked up again by the tapes 4 as it passes around the front rollers 22. This offset of this apron also causes said apron to project rearwardly of the apron 17 and thus makes a ledge on 80 which the stranded material may fall; and it also causes the aprons 19 to project forwardly of the aprons 18, forming a similar ledge. This arrangement tends to facilitate 85 the threading of the ends in between the aprons; if desired, another set of guiding rollers, not shown, may be provided in connection with the rear edge of the aprons 17. The guiding rollers 92 are held in position by short brackets 93, formed integrally with 90 the several brackets 26 and sheet metal extension 94, extending upwardly, further assist in guiding the filaments between the aprons and prevent their being picked up by the moving tapes.

95 I claim:—

1. In a machine of the class described, the combination with a dividing mechanism, of an apron rubbing mechanism comprising three or more aprons whose apron surfaces 100 are in contiguous arrangement, whereby to lead the material the length of the aprons and back again, thus to attain a supernormal rubbing action with aprons of normal length.

105 2. In a machine of the class described, the combination with a dividing mechanism, of an apron rubbing mechanism comprising four aprons whose apron surfaces are in contiguous arrangement, whereby to lead the 110 material the length of the aprons and between a pair of aprons three times, thus to attain a supernormal rubbing action with aprons of normal length.

115 3. In a machine of the class described, four aprons whose apron surfaces are in contiguous arrangement, means for reciprocating alternate aprons in opposite directions laterally, and means for causing alternate aprons to have a continuous conveying motion in opposite directions, so that the contiguous surfaces will all move in the same direction.

120 125 4. In a machine of the class described, four aprons whose apron surfaces are contiguous, one of the two middle aprons being offset with respect to the others to provide a shelf to assist in self threading of the

roving, whereby roving may be passed through the aprons three times, threading itself automatically.

5. In a machine of the class described, three or more aprons whose apron surfaces are in contiguous arrangement and adapted to lead a single length of stranded material back and forth between said aprons a plurality of times.

10. 6. In a machine of the class described, three or more aprons whose apron surfaces are in contiguous arrangement and adapted to lead a single length of stranded material back and forth between said aprons a plurality of times, and means to cause said material to thread itself between the next adjacent pair of aprons after leaving a given pair of aprons.

7. In a machine of the class described, three or more aprons whose apron surfaces are in contiguous arrangement and adapted to lead a single length of stranded material back and forth between said aprons a plurality of times, and a roller to cause said material to thread itself between the next adjacent pair of aprons after leaving a given pair of aprons.

8. In a machine of the class described, three or more aprons whose apron surfaces are in contiguous arrangement and adapted to lead a single length of stranded material back and forth between said aprons a plurality of times, and a guide plate to cause said material to thread itself between the next adjacent pair of aprons after leaving a given pair of aprons.

9. In a machine of the class described, an apron rubbing mechanism comprising three or more aprons whose apron surfaces are in contiguous arrangement and adapted to rub and condense stranded material, and means to drive said aprons at different speeds, whereby the said rubbing mechanism causes a draught on material passed back and forth between the successive aprons a plurality of times.

10. In a machine of the class described, an apron rubbing mechanism comprising three or more aprons whose apron surfaces

are in contiguous arrangement and adapted to lead a single length of stranded material back and forth between said aprons a plurality of times, and actuating means for said aprons to cause them to travel at different rates of speed, whereby to create a draught on the said material as it leaves a given pair of aprons going to the next adjacent pair.

11. In a machine of the class described, a continuous conveying and rubbing mechanism for the condensing of stranded material comprising a pair of apron surfaces moving at a given speed, and a second pair of apron surfaces one of which moves at the speed of the first pair and the other of which moves at a different speed, whereby to create a draught on said material as it goes from one pair to the other.

12. The improvement in the art of condensing carded material which consists in moving the material back and forth a plurality of times between rubbing surfaces travelling at different speeds, whereby to draw said material to a smaller diameter and obtain a more perfect condensing thereof.

75 13. In a machine of the class described, a double pair of condensing aprons, the surfaces of each pair of aprons being in contiguous arrangement, whereby to lead a single length of stranded material through one pair, then back between said pairs, then through the other pair of aprons, all of the said aprons being in substantial alinement.

14. The improvement in the art of condensing carded material which consists in moving the material in continuous contact with one or more rubbing surfaces for a specified distance, the material never being during this time out of contact with a rubbing surface, the said surface or surfaces moving at a faster rate near the end of the travel of the material than at the beginning thereof, whereby to draw and condense the material at the same time and maintain it in tension at all times because of the continuous contact.

90 JOSEPH F. SCHIMEK.
